CONVERSION OF HYDROCARBONS

Harold V. Atwell, White Plains, N. Y., assignor
to Process Management Company, Inc., New
York, N. Y., a corporation of Delaware

Application August 29, 1936, Serial No. 98,558

11 Claims. (Cl. 196—10)

- My invention relates in general to the conversion of normally gaseous hydrocarbons and more particularly to a process for producing normally liquid hydrocarbons suitable for use as motor fuel. 5 with the utilization of normally unreactive products of the process, together with similar products from an outside source, to obtain an increase in the volumetric yield above that heretofore accomplished.
- 10 It is generally recognized that methane and, to a somewhat less extent, ethane can not be converted to give commercially attractive yields of olefins for polymerization to gasoline. Some gases however, such as natural gas and residue gas 15 from low temperature oil cracking, contain large quantities of methane and ethane and it is quite desirable to provide a process for converting such gas as well as the higher paraffins and olefins to motor fuel.
- 20 An object of my invention is to provide a process wherein a gas, consisting predominantly of methane and other normally unreactive gas from a gas cracking and/or polymerization operation, is converted to increase the yield of motor fuel.
- 25 Another object of my invention is to provide a process wherein such a gas is oxidized and the products therefrom reacted with other hydrocarbons undergoing conversion.
- 30 Still another object of my invention is to provide a process wherein normally gaseous paraffinic hydrocarbons are separately converted to normally liquid hydrocarbons and normally gaseous olefinic hydrocarbons, olefinic hydrocarbons 35 therefrom being polymerized to normally liquid hydrocarbons with the unreactive gases from one or more of the stages being oxidized and the oxidized products therefrom reacted with hydrocarbons undergoing conversion.
- 40 Other objects of my invention will appear in the following detailed description.
- 45 For a better understanding of my invention, reference is now made to the accompanying drawing in which the single figure is a diagrammatic elevational view of apparatus suitable for carrying out my invention.
- 50 Referring to the single figure, I have illustrated my invention as involving three coordinated operations:
- 55 First, the conversion of hydrocarbon gases to olefins and liquid products with the aid of oxygenated hydrocarbons as promoters;
- Second, the conversion of a special fraction of residue gas from this operation to oxygenated products; and

Third, the conversion of normally liquid, but relatively low boiling hydrocarbons to higher boiling hydrocarbons mainly in the motor fuel range, with the aid of oxygenated promoters.

The first mentioned operation is illustrated in two forms. One alternative is single stage thermal polymerization, illustrated by converter 1 and its associated fractionating equipment, wherein mainly paraffinic gas is converted in a single stage with recycling to liquid hydrocarbons 10 in the motor fuel boiling range. The second alternative is a two-stage operation, illustrated by gas cracking unit 2 and olefin polymerizing unit 3, wherein paraffinic gas is first cracked to gaseous olefins for polymerization in a separate zone to 15 liquid hydrocarbons. A more detailed description of the operation of these units is given below.

A gaseous mixture consisting mainly of paraffinic hydrocarbons in the boiling range of propane and butane is supplied to converter 1, 20 which may be a conventional type of tube heater, through charging line 2' under pressure maintained by charging pump 3'. In converter 1 this gas is subjected to a temperature in the range of 1000 to 1100° F., or higher, under a pressure of 25 500 to 2500 lbs. for a sufficient length of time to accomplish simultaneous cracking of the paraffinic hydrocarbons and polymerization and other conversion of the resulting olefins to yield normally liquid hydrocarbons in the motor fuel boiling range. The products of this conversion leave converter 1 through transfer line 4 and are cooled by indirect heat exchange in cooler 5, optionally assisted by the direct admixture of quenching fluid through valved line 6. The suitably cooled 30 products are discharged into fractionator 7 from the bottom of which material heavier than the desired motor fuel product is withdrawn through valved line 8. Vapors pass from the top of fractionator 7 through line 9 into fractionator 10 from 40 the bottom of which is withdrawn through valved line 11 a heavy naphtha in the upper part of the boiling range of the desired motor fuel product. Vapors from the top of fractionator 10 pass through line 12 to fractionator 13 from the bottom 45 of which is withdrawn through valved line 14 a liquid which may be termed light naphtha, extending over the lower part of the boiling range of the desired motor fuel product. From the top of fractionator 13 normally gaseous hydrocarbons, mainly lower boiling than those desired in 50 the motor fuel product, pass through line 15 to fractionator 16 from the bottom of which is withdrawn through valved line 17 a mixture of olefinic and paraffinic hydrocarbons corresponding in 55

boiling range to the fresh gaseous charging stock supplied through line 2. These normally gaseous hydrocarbons are recycled by means of pump 18 through line 19 to the inlet of conversion unit 1 for further treatment.

From the top of fractionator 16 a gaseous mixture consisting mainly of hydrogen, methane, ethylene, and ethane is withdrawn through line 20. If it is desired to recover a portion of the ethylene content of this gas for further polymerization to liquid products, the gas is forced by pump 21 through line 22 and valved line 23 into scrubber 24, wherein it is contacted with a suitable selective absorbent supplied through valved line 25. A liquefied low boiling hydrocarbon, such as butane, may be used as the selective absorbent in this operation. Such a hydrocarbon absorbent, enriched with dissolved ethylene, is withdrawn from the bottom of scrubber 24 through line 26, and is forced by pump 27 through line 28 either through line 29 to recycle line 19 for further conversion in unit #1, or through valved line 30 to charging line 55 for further conversion in polymerizing unit 3.

Gases from which a considerable proportion of their initial ethylene content has been removed pass from the top of scrubber 24 through line 31 to secondary scrubber 32, wherein they are contacted with a heavier absorbent such as gas oil introduced through line 33 for the recovery of such light absorbent as may have been vaporized in scrubber 24. Enriched heavy absorbent is withdrawn from the bottom of scrubber 32 through valved line 34 and is pumped by pump 35 through line 36 and either through valved line 37 to transfer line 4 of converter 1 or through valved line 60 to transfer line 57 of polymerizer 3. This disposition of the enriched heavy absorbent provides a convenient means of recovering the low boiling hydrocarbons therefrom and introducing them into appropriate gas conversion zones for the formation of higher boiling hydrocarbons. However, if desired, this enriched oil may be diverted, as through valved line 38, for stripping in separate apparatus of conventional design (not shown) with return of the absorbent oil and the recovered light hydrocarbons to appropriate parts of the gas conversion system. Gas from the top of scrubber 32, consisting mainly of hydrogen, methane, and ethane is passed through line 80 to line 39 for oxidation in a manner to be described later, or may be diverted in part or in whole from the system through line 81.

Other selective absorbent or adsorbent systems may be used for recovering olefins from the gas supplied through line 23 and involving the use of either special liquid scrubbing media such as triethanol amine, or solid adsorbents such as cuprous chloride. The recovery of ethylene in systems of this character would be accomplished in a conventional manner, and the ethylene returned to either of the gas conversion zones, as illustrated in connection with absorption in liquid butane. Optionally, fractionator 16 may be operated at such a temperature that most of the ethylene is condensed with ethane and withdrawn through line 17 with the higher boiling normally gaseous hydrocarbons for recycling to conversion unit 1. In this case, the gas passing through vapor line 20 will consist predominantly of hydrogen and methane and may be diverted from line 22 through line 39 for oxidation in a manner to be described later. If desired, a part or all of this gas may be diverted from the system entirely through valved line 79.

As another feature of my process a mainly paraffinic gas having in general a lower molecular weight than the gas charged to converter 1, and consisting predominantly of ethane and propane, is supplied by pump 40 through charging line 41 to the gas cracking unit 2, which may also be a conventional form of tube heater, wherein it is heated to a temperature of 1200 to 1600° F. for a period of time generally less than one second to convert the gaseous paraffins extensively to gaseous olefins. This cracking is preferably conducted under a low or moderate pressure ranging from atmospheric to perhaps 500 lbs. Under these conditions a limited amount of aromatic hydrocarbons of the nature of benzol and toluol may be formed. The hot products leaving gas cracking unit 2 through transfer line 42 are cooled by heat exchanger 43, optionally with the assistance of quenching oil injected into the transfer line through line 44. The suitably cooled products are discharged into fractionator 45 from the bottom of which liquid hydrocarbons suitable for use as motor fuel, and heavier liquid hydrocarbons if any, are withdrawn through valved line 46 for fractionation if necessary in conventional apparatus, not shown, and for blending or other use as desired. Hydrocarbons lighter than those suitable for inclusion in motor fuel pass from the top of fractionator 45 through line 47 to fractionator 48 wherein a separation is made between the olefinic gases suitable for polymerization to liquid products and lighter gases which are not suitable for such conversion. The hydrocarbon gases suitable for polymerization are withdrawn from the bottom of fractionator 48 through valved line 49 and consist mainly of a mixture of paraffins and olefins in the general boiling range of propane, propylene, butanes, and butylenes. A gaseous mixture consisting mainly of hydrogen, methane, ethylene, and ethane passes from the top of fractionator 48 through lines 50, 51, and 23 to scrubber 24 described above. From this mixture a fraction rich in ethylene is recovered as previously described and is returned through line 30 to polymerizer 3 or through line 45 to polymerizer 1.

Fractionator 48 may be operated at a lower temperature if desired so that ethylene and ethane will be included in the bottom product withdrawn through line 49. In this case the gas escaping from the top of the tower through line 50 will consist predominantly of hydrogen and methane, and may be passed through lines 51, 52, and 39 directly to the oxidizing stage to be described later. A part or all of the gas from the top of tower 48 may be diverted from the system through valved line 53 if desired.

The olefinic hydrocarbons withdrawn from the bottom of fractionator 48 through line 49 are forced by pump 54 through charging line 55 to polymerizer 3, which may also be a conventional form of tube heater. Herein the olefinic gas is subjected to a temperature of 800 to 1100° F. under a pressure of 500 to 2500 lbs. with a sufficient time of contact to convert substantially all of the olefins to normally liquid polymers. Under some-circumstances it may be desirable to operate gas cracking unit 2 at a relatively high pressure, such as 500 lbs. or higher, and to discharge the products therefrom through by-pass line 56 directly to the polymerizing unit 3. In this case only sufficient quench oil will be introduced through line 44 to cool the products from gas cracking unit 2 to the desired temperature of 800 to 1100° F. for polymerization in unit 3, which

will be operated at a pressure only slightly below that prevailing at the outlet of gas cracking unit 2. The products from polymerizing unit 3 pass through transfer line 57 and cooler 58 to fractionator 59. Optionally the cooling of these products is accomplished in part by the introduction of the previously described cooling oil through line 60, or suitable cooling fluid from any other source through line 78. From the bottom of fractionator 59 liquid hydrocarbons heavier than those desired in motor fuel are withdrawn through valved line 61. Vapors pass from the top of fractionator 59 through line 62 to fractionator 63 from the bottom of which a liquid comprising the higher boiling constituents of the desired motor fuel product is withdrawn through valved line 64. Vapors pass from the top of fractionator 63 through line 65 to fractionator 66 from the bottom of which hydrocarbons corresponding to the lower part of the boiling range of the desired motor fuel product are withdrawn through valved line 67, and are transferred by pump 68 to line 110 for further treatment to be described later. Hydrocarbons lighter than those desired in the motor fuel product and consisting mainly of normally gaseous paraffinic hydrocarbons pass from the top of fractionator 66 through line 69 to fractionator 70. From the bottom of fractionator 70 a fraction consisting predominantly of propane and butane but with some corresponding olefins is withdrawn through valved line 71 and returned by pump 72 through line 73 to charging line 41 for the gas cracking unit 2. A gaseous mixture consisting principally of hydrogen, methane, ethylene, and ethane is withdrawn from the top of fractionator 70 through lines 74 and 75 to the charging line 23 for the ethylene recovery system previously described. However, under some conditions extensive polymerization of ethylene will occur in polymerizer 3 so that the gas escaping from the top of fractionator 70 will consist mainly of hydrogen, methane, and ethane, with little or no ethylene, and therefore will be passed through lines 74 and 76 direct to charging line 39 for the oxidizing system which will be described later. If desired, a part or all of the gas from the top of fractionator 70 may be diverted from the system entirely through valved line 77.

Gas from a variety of sources previously described and consisting mainly of hydrogen, methane, and ethane is subjected to controlled oxidation in one or two stages as its composition may indicate. If the gas contains a considerable proportion of hydrogen it is first passed through hydrogen oxidizing unit 82 containing a suitable catalyst for promoting the selective oxidation of hydrogen. Relatively pure oxygen or an oxygen-containing gas is supplied to the hydrogen oxidizing unit through line 83. This oxidation is carried out at a relatively low pressure and at a temperature of about 450-675° F., preferably in contact with a catalyst such as copper shot or copper oxide. Any suitable known conditions may be used for effecting this hydrogen oxidation, such for example as described in Patent No. 1,869,681. The products of oxidation and unconverted gases from hydrogen oxidizing unit 82 pass through transfer line 84 and are cooled by heat exchanger 85 to a temperature suitable for compression by pump 86. Pump 86 may be also supplied with gases having a relatively low hydrogen content which would not require selective oxidation of hydrogen and hence have been diverted from the previously described sources through lines 87, 88,

and 89 to supply line 90. Additional gas of similar character from any convenient outside source may also be supplied to pump 86 through line 91. The resulting mixed gas consisting mainly of methane and ethane is raised by pump 86 to a pressure of 500 lbs. to 3000 lbs. and is discharged through line 92 to the hydrocarbon oxidizing unit 93. A suitable proportion of oxygen or oxygen-containing gas is supplied also under high pressure through line 94. A suitable gaseous catalyst, such as oxides of nitrogen, may also be introduced through line 94. In oxidizing zone 93 the mixture is subjected to a temperature of 500 to 1000° F., preferably under a pressure of 500 to 3000 lbs. with or without solid catalysts, such as metallic oxides, in order to accomplish conversion of the hydrocarbons to partial oxidation products, such as methyl alcohol, ethyl alcohol, formaldehyde, acetaldehyde, acetone, etc. Any suitable known conditions may be used for effecting this oxidation, such for example as described in Patent No. 2,042,134. The products from hydrocarbon oxidizing zone 93 pass through transfer line 95 and cooler 96 to fractionator 97 wherein the liquid products of oxidation are condensed and withdrawn through line 98 and the unconverted gases and other gaseous products are withdrawn through line 99.

The oxidation products withdrawn through line 98, optionally combined with similar oxidation products from other sources, are used in a variety of ways, as will be described hereafter. The distribution of these products is accomplished by pump 100 and branch lines 101, 102, 103, and 104. Through line 101 mixed oxidation products optionally combined with similar oxidation products introduced from an extraneous source through line 105 are introduced into the charging stock for olefin polymerizing unit 3 for the purpose of accelerating the polymerization of gaseous olefins therein. Similarly, any desired proportion of the oxidation products may be supplied through line 103 to the charging line 41 for gas cracking unit 2 supplemented by similar oxidation products introduced from an extraneous source through line 106 to promote the cracking of paraffinic gas to olefins, and to permit the operation of gas cracking unit 2 at a lower temperature or with a shorter time of contact than would otherwise be required. Another portion of these oxidation products may be passed through line 104 to charging line 2' for gas polymerization unit 1, optionally supplemented with additional alcohols, aldehydes, etc., introduced through line 106 to accelerate the conversion of gaseous hydrocarbons in unit 1.

The mixed oxidation products are also used effectively by reaction with the lighter components of gasoline collected from other parts of the gas conversion system as described above. Specifically, all or part of the light naphtha made by gas conversion unit 1 instead of being withdrawn from the system through line 14 is diverted through line 107 by pump 108 for reaction with oxidation products in converter 109 also of conventional design. Likewise all or part of the light naphtha made in olefin polymerizing unit 3 instead of being diverted from the system through line 67 is forced by pump 68 through line 110 to converter 109. Additional light naphtha of similar characteristics to that obtained from these two sources may be introduced from an outside source through line 111. In converter 109 the light naphtha from these various sources is caused to react with mixed oxidation products supplied

through line 102 by means of pump 112, optionally supplemented by other similar oxidation products introduced from an extraneous source through line 113.

5 In converter 109 the light naphtha is reacted with the oxidation products under a pressure of 500 to 1500 lbs. and at a temperature of 500 to 1000° F. In addition to promoting the polymerization of certain unsaturated components of 10 the light naphtha the oxidation products also enter into reaction with the naphtha to give new hydrocarbons of higher molecular weight and high anti-knock value. In this way the low molecular weight gaseous hydrocarbons which 15 constituted the charging stock for the oxidation reaction are incorporated in the final motor fuel product whereas their conversion to liquids by pyrolysis alone would be extremely difficult. The products from converter 109 pass out through 20 transfer line 114 and cooler 115 to fractionator 116 from the bottom of which hydrocarbons heavier than the desired motor fuel product are withdrawn by pump 117 and recycled through line 118 to the charging line for converter 109. 25 A part or all of the bottoms from fractionator 116 may be diverted from the system if desired through valved line 122. From the top of fractionator 116 vapors pass through line 119 to fractionator 120 from the bottom of which a condensate having the boiling range of the desired 30 motor fuel product or blending stock therefor is withdrawn through valved line 121. Hydrocarbons and other gases lighter than the desired final condensate escape from the top of fractionator 35 120 through line 123 and may be diverted in whole or in part from the system through line 124 or may be passed through line 125 by means of pump 126 to fractionator 70 wherein they are separated for retreatment in the manner previously described.

40 From the foregoing description it will be apparent that I have provided a combination process for effectively converting hydrocarbon gases and utilizing the fixed or difficultly convertible gas resulting therefrom to form oxidation products for subjection to conversion conditions with the hydrocarbon gases and liquid products therefrom with the consequent increase in volumetric yield.

50 It is to be understood that the fractionating equipment for the converters 1, 2, 3, and 109 may be maintained at a lower pressure than that obtaining in the converters and desirably a progressively lower pressure is maintained in successive fractionators. Moreover, the number of 55 fractionators shown may be greatly reduced by providing towers with suitable trap-out trays or the like. Any desired form of cooling, such as refluxing, refrigeration, and others, may be used for each of the fractionating towers.

60 Obviously, many modifications of my invention may be made without departing from the spirit thereof and it is to be understood that my invention is not limited in scope except as 65 appearing in the appended claims.

I claim:

1. In the conversion of normally gaseous hydrocarbons to hydrocarbons of different molecular weight, wherein said normally gaseous hydrocarbons are subjected to elevated temperature and the products therefrom are fractionated to 70 separate material heavier than the desired final product from the products of conversion, the improvement which comprises fractionating the remaining products of conversion into a light

naphtha fraction, a heavy naphtha fraction and normally gaseous hydrocarbons, separating a fraction predominating in methane from said normally gaseous hydrocarbons, subjecting said fraction to an oxidizing reaction to form oxygenated compounds, utilizing oxygenated compounds thus obtained for admixture with the normally gaseous hydrocarbons undergoing conversion and separate reaction with at least a part of the light naphtha fraction. 10

2. In the conversion of normally gaseous hydrocarbons to hydrocarbons of different molecular weight, wherein said normally gaseous hydrocarbons are subjected to elevated temperature and the products therefrom are fractionated to 15 separate material heavier than the desired final product from the products of conversion, the improvement which comprises fractionating the remaining products of conversion into a light naphtha fraction, a heavy naphtha fraction and 20 normally gaseous hydrocarbons, separating a fraction predominating in methane from said normally gaseous hydrocarbons, subjecting said fraction to an oxidizing reaction to form oxygenated compounds, utilizing oxygenated compounds thus obtained for admixture with the normally gaseous hydrocarbons undergoing conversion, separately subjecting said light naphtha fraction to temperature sufficient to effect conversion thereof and admixing oxygenated compounds obtained in the process with the light naphtha fraction undergoing conversion. 25

3. A process for producing normally liquid hydrocarbons suitable for motor fuel which comprises subjecting a stream of normally gaseous 35 paraffinic hydrocarbons to elevated conditions of temperature and pressure to effect a conversion of constituents thereof to normally liquid products, subjecting another stream of normally gaseous hydrocarbons containing olefinic constituents to elevated conditions of temperature and pressure to effect conversion of constituents thereof to normally liquid products, fractionating the products from each conversion operation to 40 separate motor fuel and normally gaseous hydrocarbons, separating a fraction predominating in methane and ethane from said normally gaseous hydrocarbons, subjecting said last mentioned fraction to an oxidizing reaction to form oxygenated compounds and admixing oxygenated compounds thus obtained with at least one of said streams of normally gaseous hydrocarbons undergoing conversion. 45

4. A process in accordance with claim 3 wherein in the stream of normally gaseous hydrocarbons containing olefinic constituents is formed by subjecting paraffinic hydrocarbons to a temperature of about 1200-1600° F. 50

5. A process in accordance with claim 3 wherein in the motor fuel separated from the products of conversion is separated into a heavy fraction and a light fraction and the light fraction reacted with oxygenated compounds formed in the process. 55

6. A process in accordance with claim 3 wherein in the motor fuel separated from the products of conversion is separated into a heavy fraction and a light fraction, subjecting the light fraction to conversion conditions of temperature and pressure and admixing oxygenated compounds formed in the process with the light fraction undergoing 60 conversion. 70

7. A process in accordance with claim 3 wherein in the fraction predominating in methane and ethane is treated to remove hydrogen therefrom prior to the oxidizing thereof. 75

8. A process in accordance with claim 3 where-
in the stream of normally gaseous hydrocarbons
containing olefinic constituents is formed by sub-
jecting paraffinic hydrocarbons to a temperature
of about 1200-1600° F. and oxygenated com-
pounds are admixed therewith while being sub-
jected to said temperature.
9. In the conversion of normally gaseous hy-
drocarbons wherein said gases are subjected to
elevated conditions of temperature and pressure
to form normally liquid hydrocarbons within the
motor fuel boiling range which are separated
from remaining normally gaseous hydrocarbons,
the improvement which comprises fractionating
the thus separated gases to recover therefrom
hydrocarbons predominating in C₃ and C₄ con-
stituents and a lighter fraction containing C₂
hydrocarbons and methane, selectively treating
said lighter fraction to remove ethylene there-
from, subjecting some of the remaining constit-
uents of said lighter fraction to an oxidizing reac-
tion to form oxygenated compounds, and admix-
ing oxygenated compounds thus obtained with the
normally gaseous hydrocarbons undergoing con-
version.
10. A process in accordance with claim 9

wherein the hydrocarbons predominating in C₃
and C₄ constituents and the ethylene selectively
separated from the lighter fraction are recycled
to the gas conversion operation for conversion
into normally liquid hydrocarbons.

11. A process for producing normally liquid
hydrocarbons suitable for motor fuel which com-
prises subjecting a stream of normally gaseous
paraffinic hydrocarbons to elevated conditions of
temperature and pressure to effect a conversion
of constituents thereof, subjecting another stream
of normally gaseous hydrocarbons containing
olefinic constituents to elevated conditions of
temperature and pressure to effect conversion of
constituents thereof to normally liquid products,
fractionating the products from each conversion
operation to separate motor fuel and normally
gaseous hydrocarbons, separating a fraction pre-
dominating in methane from said normally
gaseous hydrocarbons, subjecting said last men-
tioned fraction to an oxidizing reaction to form
oxygenated compounds and admixing oxygenated
compounds thus obtained with at least one of
said streams of normally gaseous hydrocarbons
undergoing conversion.

HAROLD V. ATWELL. 25
